CLAIM

The ornamental design for a display screen with transitional graphical user interface, as shown and described.

DESCRIPTION

FIG. 1 is a front view of a first image in a sequence of the display screen with transitional graphical user interface; FIG. 2 is a front view of a second image in the sequence; and, FIG. 3 is a front view of a third image in the sequence.

The subject matter in this patent includes a process or period during which an image sequentially transitions between the images shown in FIGS. 1-3. This process or period forms no part of the claimed design.

The broken lines including the showing of the display screen of a communications terminal surrounding the illustrated design, all text, the call-out for the interactive component having the text "MENU," and the corners of the interactive component so-illustrated are included for the purpose of illustrating the environment and form no part of the claimed design.
